CLAIM

The ornamental design for a lighting module, as shown and described.

DESCRIPTION

FIG. 1 shows a front perspective view of a lighting module; FIG. 2 shows a top view of the lighting module of FIG. 1; FIG. 3 shows a right side view of the lighting module of FIG. 1;

FIG. 4 shows a left side view of the lighting module of FIG. 1; and,

FIG. 5 shows a bottom view of the lighting module of FIG. 1.

The broken line showing in the drawings is included for the purpose of illustrating portions of the Lighting Module and forms no part of the claimed design.

1 Claim, 3 Drawing Sheets(56)
